(57) **CLAIM**

The ornamental design for a roof support structure and support straps, as shown and described.

DESCRIPTION

FIG. 1 is a perspective view of a roof support structure and support straps;

FIG. 2 is a top view thereof;

FIG. 3 is a bottom view thereof;

FIG. 4 is a left side view thereof;

FIG. 5 is a right side view thereof;

FIG. 6 is a front view thereof; and,

FIG. 7 is a rear view thereof.

The roof support structure and support straps are shown with a symbolic break in its length. The appearance of any portion of the article between the break lines forms no part of the claimed design.

The roof support structure and support straps includes symbolic breaks in the straps that are illustrated in broken lines to illustrate environment and these broken lines form no part of the claimed design. The additional broken lines shown in FIGS. 1-7 illustrate portions of the roof support structure and support straps that forms no part of the claimed design.

1 Claim, 5 Drawing Sheets
